[57] **CLAIM**

The ornamental design for a bow support, as shown and described.

DESCRIPTION

FIG. 1 is a perspective view of the bow support, showing my new design;

FIG. 2 is a left side elevation of the bow support;

FIG. 3 is a right side elevation thereof;

FIG. 4 is a front elevation thereof;

FIG. 5 is a rear elevation thereof;

FIG. 6 is a top elevation thereof; and,

FIG. 7 is a bottom elevation of the bow support illustrated in FIGS. 1-6.

The bow support is shown broken away in the views for ease of illustration.
